UNITED STATES PATENT OFFICE

GEORGE M. HOLLENBACK, OF LOS ANGELES, CALIFORNIA

CASTING

Application filed February 27, 1928. Serial No. 257,520.

This invention relates to casting apparatus and relates especially to pressure casting apparatus in which a movably mounted pressure head is adapted to be brought against the mould so as to enable pneumatic pressure to act upon the mold or a cooperating melting crucible to force the molten material or metal into the mould. The pressure head may advantageously be mounted on one or more stems so as to have vertical movement and may be brought down upon the mold by pneumatic devices so that the head, which may be movably mounted in the stems, may on its contact with the mold actuate through any suitable means an automatic pressure valve to admit the pressure to the mold as soon as the pressure head is in firm contact therewith. For many purposes it is also desirable to have the pressure head automatically raised, or withdrawn, as soon as the casting pressure is relieved and a releasing spring may for this purpose act in connection with the closing piston or other pneumatic device which moves the pressure head down upon or into other cooperative engagement with the mold.

In the accompanying drawings, showing in a somewhat diagrammatic way an illustrative embodiment of this invention,

Fig. 1 is a side elevation;

Fig. 2 is a top view;

Fig. 3 is an enlarged vertical section taken substantially along the line 3—3 of Fig. 2;

Fig. 4 is an enlarged section taken at right angles to Fig. 3, and

Fig. 5 is a horizontal section taken substantially along the line 5—5 of Fig. 3.

In the form of casting apparatus which is particularly adapted for relatively small dental castings, the different parts of the device may be conveniently mounted on a suitable casing or support of cast iron or other convenient material, which may be formed with a pressure chamber 1 to which compressed air may be admitted by the supply line 44, 42 whenever the supply valve 34 is opened. See Figs. 1 and 2. If desired a suitable pressure gauge 33 may be connected with this chamber communicating with its interior by the hole 5 shown in Fig. 4. The air line 43 as shown in Fig. 1 passes into the casing 2 as shown in

Fig. 4, and has a closing valve 15 actuated by the handle or knob 32 shown in Fig. 1, so that it can be manually moved into the on and off positions. The upper extension 14 of this air line communicates through the passages 16, 17 with the closing cylinder 7, which may be formed integral with or forced into or otherwise united with the casing in any desired way so as to properly support the closing piston 10, which preferably has the releasing spring 12 beneath it so as to normally exert a raising action on this piston in connection with the cylinder end 8. This piston is provided with the connecting rod 11 bolted or otherwise secured to the lower yoke 13, to which several stems such as 39, 40 may be bolted or secured, to have vertical movement within the casing and thus operate the pressure head which may be secured thereto in any suitable way.

As shown in Fig. 3, the pressure head 20 may be loosely mounted on the head yoke 25, connecting these two stems 39, 40, one of which, such as 39, may be made hollow so as to transmit the pressure fluid from the connected flexible hose or pipe 30 communicating with the pressure chamber 1 and thus carry this fluid pressure through the cross channel 36 to the pressure valve 23, preferably normally closed as by the spring 26 and automatically actuated, it being understood, of course, that the outer end of this cross passage or bore is closed as by the screw block 38. The pressure head may be formed with a central or axial passage and with a transverse yoke such as 27 having one or more vents or air passages 28 therethrough and by bolting or otherwise securing this web to the stem 24 of the pressure valve 23, the vertical movement of this pressure head when it engages the mold 19 may be utilized to open the pressure valve at the proper time, leakage of air being of course prevented by a suitable packing or gasket 35 and by a lower seal or gasket 21 preferably of asbestos or other yielding heat resistant material, which prevents dissipation of the heat from the mold and crucible below. This mold 19 may be formed of any suitable somewhat porous material and is preferably provided

with an upper melting crucible such as 49 communicating through one or more small bore passages or sprue holes 50 with the mold chamber 51 proper below, which is of course given the desired shape for the article which is to be cast. It is also desirable to have the top of the casing formed with a suitable recess or depression such as 52 which may serve to locate or center the mold and facilitate the casting operation. In the use of this apparatus the mold may be put in position and the molten metal poured into the same, the surplus metal more or less filling the crucible 49, then the actuating handle 32 is operated so that the pressure head is quickly brought down into firm contact with the mold and the casting pressure automatically applied through the action of the pressure head as it engages the mold so that the metal is forced into the mold under predetermined air pressure. To facilitate the casting operation blow torches or other heating device may be applied to the mold in some cases before or after the pressure head is brought down, which serves to heat these relatively small molds and still further insure uniform high-grade castings. For some purposes it is desirable to allow the mold to cool before the pneumatic casting pressure is released and which effects the upward removal of the pressure head through the action of the releasing spring as previously described.

This invention has been described in connection with a number of illustrative embodiments, forms, proportions, parts and methods of operation and use to the details of which disclosures the invention is not supposed to be limited because what is claimed to be new and what is desired to be secured by Letters Patent is set forth in the appended claims.

Having thus disclosed my invention, I claim and desire to secure by Letters Patent:

1. The dental casting apparatus comprising a unitary casing formed with a pressure chamber and with a closing cylinder, a closing piston operating in said cylinder and having a releasing spring normally raising the same into released position, a lower yoke and a pair of stems having their lower ends connected with said piston and mounted to move vertically in said casing, a head yoke connected to said stems, a pressure head loosely mounted on said head yoke, one of said stems being hollow and communicating with said pressure chamber, a normally closed pressure valve operatively connected with said pressure head to be automatically opened when said pressure head is forced down into contact with the mold to thereby put said mold under pneumatic casting pressure.

2. The dental casting apparatus comprising a unitary casing formed with a pressure chamber and with a closing cylinder, a clos-

ing piston operating in said cylinder and having a releasing spring normally raising the same into released position, a yoke and a stem connected with said piston and mounted to vertically move the said casing, a pressure head loosely mounted on said stem and having a seal and a central perforation, a normally closed pressure valve operatively connected with said pressure head to be automatically opened when said pressure head is forced down in contact with the mold to thereby put said mold under pneumatic casting pressure.

3. The dental casting apparatus comprising a unitary casing formed with a pressure chamber and with a closing cylinder, a closing piston operating in said cylinder and having a releasing spring normally raising the same into released position, a lower yoke and a stem having its lower end connected with said piston and mounted to move vertically in said casing, a head yoke connected to said stem, a pressure head loosely mounted on said head yoke and having a perforated seal, a normally closed pressure valve operatively connected with said pressure head, said stem being hollow and communicating between the pressure chamber and pressure valve, said pressure valve to be automatically opened when said pressure head is forced down into contact with the mold to thereby put said mold under pneumatic casting pressure.

4. The dental casting apparatus comprising a casing formed with a pressure chamber; a cylinder, a piston operating in said cylinder, a resilient means urging the piston in one direction, a hollow stem connected with said piston and mounted to move in said casing, a pressure head communicating with said pressure chamber through said hollow stem, a normally closed pressure valve operatively connected with said pressure head to be automatically opened when said pressure head is forced down into contact with the mold to thereby put said mold under pneumatic casting pressure.

In testimony whereof, I have signed my name to this specification.

GEORGE M. HOLLENBACK.
